ELECTRICAL CONDUCTOR CLAMP
Arthur Vincent Tracy, Box 136, New Gretna, N.J.,
assignor of one-half to Mildred M. Tracy, New
Gretna, N.J.

Filed Oct. 10, 1963, Ser. No. 315,210
5 Claims. (Cl. 339—266)

The instant invention relates generally to electrical connectors and is more particularly concerned with a clamp for an electrical conductor or cable.

It is a primary object of the instant invention to provide a conductor clamp which is capable of quickly and positively engaging the stripped end of a conductor.

In conjunction with the above object, it is an object of the invention to provide a device which effects the desired clamping in a solderless and vibration proof manner.

Further, it is a significant object of the instant invention to provide a device which effects the desired clamping without any danger of shearing or marking the conductor.

In addition, it is an object of the instant invention to provide a conductor clamp which is generally simple in structure and capable of economic manufacture.

In order to accomplish the above objects, it is intended that the device of the instant invention be formed in two parts or of two members, one rotatably received over the other with a conductor receiving passage extending through both members and having abutment means located therein in a manner so as to, in a first position, allow the insertion of the stripped end of a conductor and, in a second position, clampingly engage the end of the conductor so as to prevent its withdrawal.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a side elevational view of the electrical conductor clamp of the instant invention joining an electric conductor or cable to a terminal post;

FIGURE 2 is a top plan view of the invention as illustrated in FIGURE 1;

FIGURE 3 is a cross sectional view of the clamp with the members rotated so as to allow for the introduction of the conductor;

FIGURE 4 is an end view of the device in its installed position;

FIGURE 5 is a cross sectional view taken substantially on a plane passing along line 5—5 in FIGURE 2;

FIGURE 6 is a cross sectional view taken substantially on a plane passing along line 6—6 in FIGURE 1;

FIGURE 7 is an exploded perspective view of the two gripper members forming the clamp of the instant invention; and

FIGURE 8 is a cross sectional view taken substantially on a plane passing along line 8—8 in FIGURE 2.

Referring now more specifically to the drawings, reference numeral 10 is used to generally designate the electrical conductor clamp comprising the instant invention, this clamp being utilized in the joining of an electrical conductor or cable 12 to a terminal post 14, the clamp being grippingly engaged with the stripped end portion 16 of the conductor 12 and fastened to the terminal post 14 by suitable means such as the nut 18.

The clamp 10 of the instant invention consists solely of two gripper members 20 and 22. The first or lower gripper member 20 includes a flat generally rectangular base 24 having two vertically extending spaced parallel walls 26 and 28 integral with one end portion of the base 24. These walls 26 and 28, as will be appreciated from the drawings, are generally circular in shape and have

2

approximately one-half of the area thereof positioned forward of the forward end 30 of the base 24, the rear edge 32 of each of these walls projecting tangentially downward from the rearmost point on the circumference of the walls and perpendicular to the flat base 24. One of these walls, wall 26, is provided with an arcuate notch or recess 34 at its upper end, the purpose of which shall be gone into subsequently.

With reference specifically to the cross sectional views 10 of FIGURES 3 and 5 and the perspective view of FIGURE 7, it will be noted that a transversely extending raised and forwardly projected bottom wall 36 is provided between the spaced parallel walls 26 and 28. The top surface 38 of this bottom wall 36 slopes downwardly 15 and forwardly from a rear convex edge or camming surface 40 located slightly forward of the vertical plane of the rear edges 32 of the side walls 26 and 28. The forward edge of this top surface 38 terminates coextensively with the adjoining walls 26 and 28 with the bottom surface 42 of the forwardly projecting portion of the bottom wall 36 following the curvature of the walls 26 and 28 and terminating in the front edge 30 of the base 24.

The second or upper gripper member 22 includes a flat base 44, a vertically extending wall 46 integral with the forward end of the base 44, and an arcuately formed forwardly and downwardly extending portion 48 integral with the upper end of the vertical wall 46 and having a radius of curvature corresponding to that of the walls 26 and 28, this portion 48 being of a width so as to span both 30 walls 26 and 28 and the space therebetween. Aligned apertures 50 and 52 are provided through both the forward portion of the arcuate portion 48 and the vertical wall 46, these apertures 50 and 52 being of a size so as to enable the introduction of the cable end 16 therethrough. 35 In addition, with reference to FIGURES 3, 5 and 8, it will be noted that a projection or abutment 54, integrally formed with the gripper member 22, is located so as to extend radially inwardly from the top of the arcuate portion 48 between the side edges thereof in a manner so as to 40 allow for its reception between the walls 26 and 28 in the assembled clamp. Inasmuch as this projection or abutment 54 is to directly engage the conductor end 16, the lower end thereof is arcuately or convexly formed so as to prevent any damage to the conductor 12 while still 45 providing for the desired clamping engagement and shall be gone into in detail presently.

The upper gripper or clamping member 22 is engaged with the lower member 20 by a lateral movement of one relative to the other, the abutment projection 54 entering 50 into the space between the walls 26 and 28 through the recess or notch 34 in the wall 26. As will be appreciated from a comparison of FIGURES 3 and 5, the terminal edge 56 of the arcuate portion 48 is located so as to allow for a rotational movement of the member 22 relative to the member 20 between a first position wherein this edge 56 abuts against the forward edge 30 of the base 24, and a second position wherein the base 44 is positioned in engagement with the upper surface of the base 24, the inner vertical surface of the wall 46 engaging 55 against the vertical edges 32 of the side walls 26 and 28 thus further rigidifying the closed or gripping position of the clamp 10.

In utilizing the clamp 10 of the instant invention, the member 22 is first rotatably engaged with the member 20 and subsequently rotated to the first position illustrated 60 in FIGURE 3 wherein the aligned apertures 50 and 52 are orientated along a generally downwardly angled center line conforming to the sloping surface 38 with the surface 38 being generally in the plane of the lowermost portions of the apertures 50 and 52 so as to allow for the introduction of the conductor end 16 through both the apertures 50 and 52 and the passage or space between the

walls 26 and 28, a slight compressing of the cable end 16 allowing for its movement past the abutment projection 54. After the conductor end 16 has been inserted, the upper member 22 is rotated to the position illustrated in FIGURES 1 and 5 which results in an engagement of the conductor end 16 with the convex camming surface 40 resulting in a compression of the end 16 between the surface 40, the projection 54 and that portion of the vertical wall 46, indicated by reference numeral 58, located immediately above the inner end of the aperture 52 thus providing for a three point engagement productive of a firm clamping of the cable end 16. In this position, the clamp 10 is positioned so as to locate the terminal 14 through aligned apertures 60 and 62, one in each of the flat bases 24 and 44, with the bases being secured to the terminal 14 by the nut 18. As will be appreciated, such an arrangement provides for a simple though highly novel connecting of an electrical conductor to a terminal post, this connection being simply effected and extremely efficient.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A conductor clamp comprising first and second gripper members, said first gripper member including a base, a pair of spaced parallel generally circular walls projecting from the base, and an abutment means extending upwardly from said base between the parallel walls, said second gripper member including a relatively wide arcuately formed portion rotatably engaged over the walls and enclosing the space therebetween, a pair of aligned apertures through said portion, one aperture being aligned with and communicated with each end of the space between the parallel walls for enabling the introduction of a conductor therethrough, a second abutment means on said second gripper member extending downwardly between the parallel walls and generally toward the first abutment means, said second gripper member being rotatable between a first position wherein said second abutment means is positioned relative to the first abutment means a distance sufficient so as to allow for the aforementioned introduction of the conductor through the apertures and passage, and a second position wherein said second abutment means is positioned relative to the first abutment means in a manner so as to effect a clamping of the conductor therebetween.

2. The device of claim 1 including a recess in one of the first gripper member walls of a size so as to allow for the passage of the second abutment means therethrough, thereby enabling a lateral engagement and disengagement of the second gripper member with the first gripper member.

3. The device of claim 2 including means for limiting the rotational movement of the second gripper member and means for releasably securing said second gripper member in the second position.

4. The device of claim 1 wherein the base of the first

gripper member projects outward from between the parallel walls, said second gripper member including a flat base projecting outwardly from the arcuately formed portion into overlying relationship with the first mentioned base in said second position, said bases having aligned apertures therethrough, and releasable fastener means extending through the base apertures for securing said second gripper member to the first gripper member in the second position.

5. A conductor clamp comprising first and second gripper members, said first gripper member including a base, and fixed abutment means positioned transversely on the base and projecting upwardly therefrom, said second gripper member including a base, a generally vertical wall projecting upwardly from one end of the second member base, said second member base being positioned on the first member base with the vertical wall to one side of the abutment means, a wall portion integral with the upper end of the vertical wall and projecting forwardly therefrom in spaced relation above said abutment means, second abutment means fixed to and depending from the forwardly projecting wall portion toward the general plane of the first abutment means and on the other side thereof from the vertical wall, said forwardly projecting wall portion terminating in a depending portion adjustably engaged with the first gripper member in a manner so as to allow an upward pivoting of the second gripper member along with the vertical wall and forwardly projecting wall portion, and consequently the second abutment means, and a pair of aligned apertures through the vertical wall and the depending portion, said apertures being aligned with the space between the two abutment means so as to form a through passage for the introduction of a conductor between the two abutment means and through the two apertures, said second gripper member being pivotal between a first position wherein said second abutment means is positioned relative to the first abutment means a distance sufficient so as to allow for the aforementioned introduction of the conductor between the abutment means and through the apertures, and a second position wherein said second abutment means is positioned relative to the first abutment means in a manner so as to effect a clamping of the conductor therebetween, the portion of the vertical wall defining the upper limit of the aperture therethrough effecting a clamping of the conductor between this portion and the first abutment means when the second gripper member is in the second position, thereby effecting a three point clamping of the conductor with the first abutment means engaged with one side of the conductor, and with the second abutment means and the aperture defining portion of the vertical wall, located to each side of the first abutment means, engaged with the opposite side of the conductor.
